(Cl. D56—4)

To all whom it may concern:

Be it known that I, Horace Terrell, a citizen of the United States, residing at New York city, county of New York and State of New York, have invented a new, original, and ornamental Design for a Radio Receiver Cabinet, of which the following is a specification, reference being had to the accompanying drawing, forming part thereof.

The figure is a perspective view of a radio receiver cabinet embodying my new design.

The rear portion and the end portion, not shown, are plain.

I claim:

The ornamental design for a radio receiver cabinet, as shown and described.

HORACE TERRELL.
